FRAME FOR A MOBILE IRRIGATION DEVICE

David Kane, 5036 Roosevelt Ave., San Antonio, Tex.

Filed Nov. 4, 1964, Ser. No. 82,474

Term of patent 14 years

(Cl. D40—1)

FIGURE 1 is a perspective view of the frame for a mobile irrigation device showing my new design; and FIGURE 2 is a side elevational view thereof, the dot-dash showing being for illustrative purposes only.

I claim:

The ornamental design for a frame for a mobile irrigation device, substantially as shown and described.
